UNITED STATES PATENT OFFICE

108,858

DESIGN FOR A DRESS ENSEMBLE

Jacob Abbate, New York, N. Y.

Application January 18, 1938, Serial No. 74,380

Term of patent 3½ years

To all whom it may concern:

Be it known that I, Jacob Abbate, a citizen of the United States, residing at 50 Central Park South, in the county of New York, and city and State of New York, have invented a new, original, and ornamental Design for a Dress Ensemble, of which the following is a specification, reference being had to the accompanying drawing, constituting a part thereof.

Fig. 1 is a front view of the dress ensemble.

Fig. 2 is the rear view of the dress ensemble as shown in Fig. 1.

The back of the blouse section and the balance of the front are conventional.

The characteristic feature of my design resides in the combination on the ensemble disclosed of the specific jacket member which is embroidered as shown, in association with a cowl necked dress having a triangular patch of shirring at the waistline and a skirt which is stitched and pleated as shown.

I claim:

The ornamental design for a dress ensemble substantially as shown and described.

JACOB ABBATE.
